STOPPER FOR NONREFILLABLE
RECEPTACLES

Robert Petrone, Chicago, Ill.

Application November 9, 1940, Serial No. 365,064

2 Claims. (Cl. 215—25)

This invention relates to devices for preventing the refilling of bottles, carboys, jugs and other liquid containers.

The principal object of the invention is the provision of a stopper or closure for a container provided with mechanism that is so constructed that it cannot be manipulated into such position that a liquid can be introduced into the container nor into such position that the mechanism may be tampered with for introducing a liquid into such container, such mechanism being so constructed that any liquid put in the container before the improved stopper is applied may be poured therefrom.

A further object of the invention is the provision of a non-refillable stopper or closure for a container that is inexpensive to manufacture, is easily assembled, efficient in operation, composed of few moving parts and one that will prevent the introduction of a liquid into the container but will permit the liquid in the container to be discharged therefrom in a minimum amount of time.

Other and further objects and advantages of the invention will appear from the following description, taken in connection with the accompanying drawing, in which—

Fig. 1 is a vertical section of a container showing the invention in position therein;

Fig. 2 is a section on the line 2—2 of Fig. 1;

Fig. 3 is a section on the line 3—3 of Fig. 1;

Fig. 4 is a vertical section of a modified form of the invention;

Fig. 5 is a vertical section of a further modified form of the invention;

Fig. 6 is a section on the line 6—6 of Fig. 5; and

Fig. 7 is a vertical section of a still further modified form of the invention.

Producers or manufacturers of liquids that have attained considerable reputation often suffer loss of sales by unscrupulous persons that refill the containers bearing these reputable trademarks, trade-names, or other identifying insignia, with an inferior liquid and sell the same as from the original manufacturer or producer.

Various devices have been proposed for remedying this difficulty by the provision of mechanism for preventing the refilling of the containers but they have been inefficient, or if efficient, they have been so complicated that the cost of manufacturing and applying the same has been unprofitable and in some cases prohibitive.

The present invention seeks to remedy this situation by the provision of a new and improved

stopper or closure that is inexpensive to manufacture and efficient in use.

Referring now to the drawing, the reference character 10 designates a container such as a bottle, jug, carboy, or the like, of glass, earthenware, or other suitable material, which has its upper portion provided with the neck 11 having an axial opening or passage 12, as is usual in such constructions. The axial opening 12 is adapted to be closed by a stopper, plug or closure 13 which is adapted to be secured in place by any suitable means, such as cement or the like, for permanently holding the member in position.

The stopper or closure 13 comprises a lower section 14, Fig. 1, and an upper section 15 which may be cemented together, if desired. The upper section 15 has a cylindrical portion adapted to be inserted in the container opening and a flange portion 20 that seats on the end of the neck for limiting the inward movement of the closure or stopper. A gasket 200 is inserted between the flange 20 and the end of the neck 11 for sealing the joint between the neck and flange. The section 15 is also provided with a recess, passage or opening 16 in which a conventional cork or other stopper may be inserted. This passage extends longitudinally through the section and its lower portion is reduced in diameter. The lower end of the upper section 15 is reduced to form a downwardly extending axial projection or reduced end 17 which is adapted to extend downwardly into a counterbore 18 formed in the upper end of the lower section 14, as clearly shown in Fig. 1 of the drawing. The reduced end 17 forms a shoulder 19 which is adapted to seat on the upper end of the lower section 14.

The upper end of the lower section 14 is provided with an annular groove 21 and the upper section is provided with a bore 22 which, when the parts are assembled, will be in communication with the groove 21 in any angular position to which the upper section may be turned. The lower section 14 is provided with a vertical bore or passage 23 which is also in communication with the groove 21. The bore 23 extends entirely through the lower section 14 lengthwise thereof and has its lower end enlarged laterally in one direction as shown at 24 in Fig. 1. The enlarged portion 24 of the bore 23 has secured in the lower end thereof, a tubular member 25 which has a valve seat 26 formed in its upper end. A ball valve 27 engages the valve seat 26 for closing the bore 28 of the tubular member 25. The ball 27 is adapted to prevent the entrance of air or any

fluid into the container but is adapted to open the passage when the container is inverted for admitting air to replace the liquid in the container. A spur or projection 29 extends downwardly into the enlarged space 24 so that when the container is inverted, this spur will prevent the ball from seating and closing the bore or passage 23. It will thus be seen that when the container is inverted, that air may enter into the container to replace the liquid by passing down the bore or passage 22, which is preferably offset from the passage 23, thence around the channel 21, along the passage 23, past the valve 27 and finally through the passage 28 into the container.

The lower section 14 of the stopper is provided with an axial passage or bore 160 which extends entirely through said section axially thereof. The upper portion of this bore is enlarged as at 18 and the intermediate portion 31 is of smaller diameter than the upper portion thus forming the annular shoulder 32 on which the deflector member 33 is adapted to seat. The lower portion 34 of this passage is further reduced in diameter to form the annular seat 35 on which the main valve 36 is adapted to seat. The walls of the bore 160 are further restricted at their lower ends to form a valve seat 37 on which a secondary valve 38 is adapted to seat.

The deflector member 33 comprises a disk 39, Fig. 2, and this disk has attached thereto, about its periphery, spacer arms 41 which extend radially from the deflector 33 and rest on the shoulder 32, as clearly shown in Figs. 1 and 2 of the drawing. The arms or projections 41 are extended upwardly, as shown at 42 in Fig. 1 so as to space the disk 33 from the lower end of the upper section 17 to provide a passage for the liquid contained in the container when the latter is inverted, as will presently appear. The diameter of the disk 33 is less than that of the intermediate section 31 of the passage so that when the container is inverted, liquid may pass upwardly through the space formed between the disk 33 and the shoulder 32, as will be clear from an inspection of Figs. 1 and 2.

The valve 36 comprises a disk 43 having an axially depending stem portion 44 having an axial bore or passage 45 extending upwardly therein. The stem 44 has arms or fins 46 radiating therefrom as shown more clearly in Fig. 3. These fins guide the valve to its seat in its vertical movement without materially interfering with the flow of liquid through the valve when the same is opened which may be done by inverting the container.

The valve 38 comprises a semi-circular head portion 47 which may be in the form of a hollow hemisphere of Monel metal or other suitable material which will not be chemically affected by the liquid in the container. The stopper sections, deflector and valve 36 may, if desired, be of porcelain or other sealable material. The head 47 is provided with a valve stem 48 which extends upwardly into the bore or passage 45 of the stem 44 of the valve 36 for guiding the valve 38 in its vertical movement.

The valves 36 and 38 are seated when the receptacle 10 is in upright position and when it is desired to remove the liquid from the container, the stopper in the recess 16 is removed and the container inverted which will unseat the valves 38 and 36. The liquid will then pass along the bore or passage 160, past the valve 47, laterally and longitudinally around the

valve 36, and then will pass laterally upwardly and inwardly around the deflector 33 and out through the axial bore 16. In the meantime, the valve 27 will have been unseated and air 5 will pass down its passage 22, as viewed in Fig. 1, around the groove 21 and down the passages 23 and 28 for replacing the liquid. In order to hold the valve 38 by gravity on its seat when the receptacle 10 is in upright position, an annular weight member 49, having an axial opening 10 and 15 therein, is mounted on the stem 48.

It will thus be seen that should an unauthorized person attempt to refill the container by inverting the same and forcing the liquid through 15 the passage 16, the light valve 38 will tend to float on top of the liquid and close the passage 160 for preventing this operation. Should an attempt be made to fill the container while in upright position, both valves 36 and 38 will be 20 closed for preventing this operation. The weight member 49 will close the valve 38 when the container is in upright position but will rest on the valve 36 and be ineffective when the container is inverted. It will be noted that the 25 tortuous path of the passage lengthwise the stopper is such as to prevent anyone from thrusting a wire or the like down the passage for opening the valves 36 and 38 or either of them.

The passage 22, 23, 28 is so small and long 30 and tortuous that there is not much likelihood of anyone attempting to refill the container through this passage. However, a valve 27 is provided which will close by gravity when the container is in upright position and will be seated by the force of the moving liquid if it is 35 attempted to refill the container while in inverted position.

A suitable cap 30 is provided which may be 40 threaded onto the neck 11 of the container 10, as shown in Fig. 1. This cap has an axial opening which extends about the stopper opening 16 and is of larger diameter than the opening 16 whereby the same may contain a sealing material or the like bearing the manufacturers seal. This cap may also be cemented in position so 45 that it may not be removed.

The ball valve 27 is also preferably of light 50 material but not light enough to float in liquids of low specific gravity so that if an attempt is made to force a liquid into the container while the same is in inverted position, the movement of the liquid will carry the valve to its seat thus stopping the movement of the liquid through the passage 28.

The form of the construction shown in Fig. 4 55 differs from that shown in Fig. 1 in that the valve 360 in the stopper 130 between the upper and lower sections thereof is provided with a concave recess 51 and the spacer member 180 has its lower surface correspondingly convex for forming a space 52 in which a ball 53 is mounted. The ball 53 will hold the valve 360 on its seat even though the container be inverted. A recess 54 is provided in the adjacent wall of the 60 lower section 140 of the stopper. Since the remainder of the structure is substantially the same as that already described, it is not thought necessary to further illustrate or describe the same except to state the valve 470 is not weighted.

Anyone knowing the construction may remove the liquid from the container by first moving the container to horizontal position with the recess 65 or pocket 54 turned down. The ball 53 will run

into the pocket and the container may be turned further into inverted position whereby the valve 360 will move to open position.

In Fig. 5 is shown a modified form of construction and in this form of the device, the stopper 55 is a one-piece structure having a cylindrical transverse opening 56 through its intermediate portion in which is mounted a cylindrical plug 57. The stopper 55 is provided with a longitudinal axial opening 58 which extends throughout the length of the stopper and this bore or passage is enlarged as at 59 for receiving a conventional stopper or any suitable closure. The passage is restricted as at 61 and the plug 57 is provided with a spherical intermediate portion 62 opposite 18 the restricted opening 61, as clearly shown in Fig. 5 of the drawings.

The spherical portion 62 is provided on its undersurface with an upwardly extending annular recess 63 into which the upper reduced end 64 of a cylindrical insert 65 extends. The insert 65 is rigidly mounted within the lower end of the bore 58 and has a valve seat member 66 secured in its lower portion. The valve seat member 66 is provided with an axial passage or bore 67 and the upper end of the valve seat member is provided with a valve seat 68 on which is seated the valve 69. The valve 69 is hollow and has a stem 71 attached thereto which extends upwardly into the reduced end or neck 64 of the insert 65 which forms a guide for said valve. The valve 69, being hollow, is light but not light enough to float so that when the container in which the stopper 130 is used is inverted, liquid may not be forced upwardly into the container because the valve, being light, will seat and close the passage 61. The weight of the liquid, when the container is inverted, will cause the same to unseat the valve and flow through the passage 58 from the container.

It will be seen that the liquid, when poured from the container, will pass through the passage 61, the insert 65, and flow upwardly and then downwardly around the restricted wall 64 of the insert and then upwardly around the spherical member 62, through the passages 72, Fig. 6, and thence through the restricted passage 61 and passage 59. It will also be noted that the path through which the liquid passes is a sinuous one and as a result, the valve 69 may not be unseated by the manipulation of a wire or other member thrust downward through the passage.

Suitable means are also provided for permitting the entrance of air into the container for displacing the liquid contained therein. As shown, the upper and lower portions of the stopper 130 are provided with aligned passages 73 and 74 and the plug 57 is provided with an annular passage 75 which is in communication with the passages 73 and 74. The lower end of the passage 74 is counterbored and has attached thereto a tubular member 76 which has its lower end enlarged as at 77 for containing a valve 78. A valve seat member 79 is inserted in the lower end of the enlarged portion 77 of the tubular member and is provided with a valve seat on which the valve 78 rests. A pin 790 may be inserted transversely across the enlargement of the tube 76 for limiting the upward movement of the valve so that it cannot close the passage leading from the enlargement into the upper portion of the tubular member 76 when the receptacle is inverted. Like the previous construction, the passages 73 and 74, through the stopper are very small in diameter so that practically no liquid can be inserted through

this passage and none escapes when the container is inverted.

In Fig. 7 is shown a further modified form of the construction and in this figure, the stopper member 81 is made in two parts, as in the construction shown in Fig. 1. The upper portion 82 is constructed similar to the upper portion 15 of the stopper shown in Fig. 1 and it is not thought necessary to repeat the description.

The lower section 83 of the stopper has an axial bore 84 extending throughout the length of the lower section which is in alignment with the reduced portion 85 of the passage 86 of the upper section, as shown in said figure. The reduced end 87 of the upper section is adapted to fit in the upper portion of the bore of the lower section, as in the previous construction. The upper portion of the passage 84 is enlarged to form shoulders 88 on which is seated a spacer member 89. The spacer member 89 comprises an inverted cup-shaped portion 91 which is provided with radially extending arms or projections 92 which are adapted to be seated on the shoulder 88. The cup-shaped portion 91 is of less diameter than the opening of the passage below the shoulders so as to form an annular space 93 about said cup-shaped member for the passage of the liquid from the container. The arms 92 are extended upwardly to provide a space 94 between the upper section 82 and the cup-shaped portion 91 of the spacer 89.

The lower portion of the bore 84 is further reduced to form a shoulder 96 on which a valve supporting member 97 is adapted to seat. The valve supporting member 97 is rigidly mounted in the passage 96 and is provided with an upstanding portion 98 having an axial opening therein. A valve member 99 is seated on the upper end of the upstanding portion 98 of the valve support 97. This valve member has a depending stem 101 in the form of an X in cross-section which guides the valve within the bore of the valve seat member. The lower end of the lower section 83 is provided with a valve seat 102 reduced in diameter on which a valve 103 is adapted to seat. This valve will prevent the entrance of fluid into the container.

The upper and lower sections of the stopper are provided with passages 104 and 105 arranged as in the construction shown in Fig. 1. A valve 106 is also provided as in the previous construction. When the container in which the stopper is used is inverted, the valve 103 will become unseated and likewise the valve 99. The liquid then will pass upwardly past the valve 103, through the opening in the valve seat 97 and downwardly around the lower edge of the cup 91, and thence upwardly through the passage 93, the space 94 and the restricted passage 85 from the container.

It will be noted that in all forms of the device, the liquid, when poured from the container, flows along a sinuous or winding path, that is, it flows first axially outwardly, then radially outwardly, then axially outwardly, then radially inwardly and finally axially outwardly axially from the container.

It is thought from the foregoing, taken in connection with the accompanying drawing, that the construction and operation of my device will be apparent to those skilled in the art and that changes in size, shape, proportion and detail may be made without departing from the spirit and scope of the appended claims.

I claim as my invention:

1. In combination, a container having a neck provided with an axial opening, said container

being adapted to contain a liquid, a sectional stopper within said opening, said stopper comprising a lower body portion having an axial passage therethrough leading to said container, said passage being restricted at its lower end to form a valve seat, a valve for said seat for closing said passage against the entry of a liquid to said container, said valve having an upwardly extending stem, said valve being light enough to float in said liquid, a weight loosely mounted on said stem, a guide for said stem, an air passage formed by a groove in one of the sections of said stopper and extending through said stopper, said passage having its intermediate portion curved through a large number of degrees, a valve within said air passage for admitting air to said container only when said container is inverted, and means for preventing a liquid from traveling in a straight line from said container to the exterior thereof when the same is inverted.

2. In combination, a container having a neck provided with an axial opening through which a liquid is introduced into said container, means insertible in said opening to form two separate passages, one of said last-named passages consti-

tuting a liquid passage through which a liquid may pass when said container is inverted and the other an air passage for introducing air into said container when the same is inverted, said 5 means including a stopper comprising an upper section and a lower section, said sections having aligned axial passages forming said liquid passage, a deflector between said sections in an intermediate portion of said liquid passage and intercepting the same, a main valve seated in said liquid passage beneath said deflector, said main valve having a stem provided with radially extending guiding fins for positioning said valve, a secondary valve in said liquid passage below said main valve, said valves cooperating to prevent the entrance of a liquid into said container when the latter is in upright position, said air passage being formed by a groove in one section of said stopper and curved through at least 180° in a plane transverse to the longitudinal axis of the container and in communication with a straight passage in each of said sections, and means associated with said air passage for preventing the entrance of air in said container when same is in upright position.

ROBERT PETRONE.
